UNITED STATES PATENT OFFICE

LEON C. KOENIG, OF CUDAHY, WISCONSIN, ASSIGNOR TO HEVI DUTY ELECTRIC COMPANY, OF MILWAUKEE, WISCONSIN, A CORPORATION OF WISCONSIN

POT FURNACE

Application filed April 24, 1928. Serial No. 272,365.

My invention relates broadly to furnaces and more particularly to electric furnaces of the pot type.

One of the objects of my invention is to provide a construction of pot type furnace in which the heat flow from the pot of the furnace to the metallic top plate of the furnace is prevented by interposing a non-metallic, flexible and compressive packing between the flange of the pot and the supporting projection of the top plate of the furnace.

Another object of my invention is to provide a sealing means between the annular periphery of a pot type furnace and the heating system thereof, by applying a packing ring between the periphery of the upper edge of the pot and the heating chamber for distributing the weight of the pot and its contents more uniformly on the supporting projection 20 of the top plate.

Still another object of my invention is to provide an arrangement of highly compressive packing ring disposed between pre-formed peripheries of the heating chamber 25 and the pot furnace in order to prevent molten or fluid material, such as lead or fluid salts, or the fumes thereof, from getting into the furnace chamber outside the pot where such fluids or gases might be detrimental to 30 the furnace walls or heating means.

The structure of my invention will be more fully understood from the specification hereinafter following by reference to the accompanying drawings, in which:

Fig. 1 is a transverse section through a pot type furnace partly in elevation showing my invention applied thereto; and Fig. 2 is an enlarged section through that portion of the pot furnace of my invention wherein the 40 packing ring is lodged.

Referring to the drawings in more detail, the walls of the furnace are formed from a refractory material 1 enclosing the furnace chamber 20. Reference character 9 indicates the top plate which may be formed from cast iron supporting a suspended pot 4, which may be of cast iron, pressed steel or cast of a non-oxidizing metal. Interposed between the downward extending annular flange 4^b of pot 4 and the upward turned sup-

porting portion 8 of top plate 9, is a packing ring 6 formed from such material as asbestos, either in the twisted or braided form.

The furnace is shown heated electrically by means of coils 3 housed within the refractory walls 1, though any other suitable furnace chamber heated by fuel may be used. The upwardly extending annular peripheral portion 8 of top plate 9 is preferably grooved or shaped at its extremity to better support and compress the packing ring 6. The annular upstanding edge 8 is actually dished or formed with a concave upper peripheral face which confines the compressible ring member 6 to a definite position with respect to the pot type furnace. The underside of the annular peripheral edge 4^b of the pot 4 is concave downwardly while the upper peripheral edge 7 is concave upwardly.

The weight of the pot 4 with its contents 70 highly compresses the flexible packing 6, which distributes the weight more uniformly on the supporting upwardly extending portion 8 of top plate 9 than would exist where a comparatively rough casting having such upturned portions would bear only in a few locations on the underside of lip 4^a. This reduces the stresses that would otherwise be set up by an unequal distribution of weight. The same compressive action tends to seal the 75 furnace chamber from inflow of any fluid such as molten lead, molten salt, etc.

The packing ring disposed between the annular periphery of the pot furnace and the heating chamber has been found to be extremely practical in cutting down heat losses 85 by radiation due to breaking up the heat flow by direct contact between the pot and the top plate of the furnace. It has been found effective also in sealing the furnace chamber from 90 the influx of gases, fluids, etc.

Heretofore it has been proposed to cement by any material such as fire clay, the junctions between the pot and the top plate. The inequalities of expansion, however, between the 95 pot which obviously may be at a high temperature and the top plate of the furnace, which may be at a comparatively lower temperature, tends to break up such refractory cement and destroy its effectiveness. The 100

compressible packing ring which I employ forms a sealing zone which is substantially permanent in character, not subject to cracks and breakage under conditions of temperature change.

The top plate 9 may fit telescopically over the outer plate 2 of the furnace as shown at 10 for centering the plate on the furnace structure. The annular rim 4^a—4^b is so shaped 10 as to form a substantially inverted U having a rim seat 5 and a skirt portion 4^b for confining the compressible ring member 6 between the rim seat 5 and the coating seat 7.

The structure of my invention has proven 15 highly practical in use, and while I have described a preferred embodiment of my invention, I desire that it be understood that modifications may be made and that no limitations are intended other than are imposed by the 20 scope of the appended claims.

What I claim as new and desire to secure by Letters Patent of the United States is as follows:

1. In a pot type furnace a housing terminating in an upstanding annular member, a seat formed in said annular member, said seat extending upwardly at each edge thereof and having a central portion disposed at a level lower than the level of the edges of the seat, 25 a pot type receptacle having a rolled-over edge terminating in a depending skirt for providing an annular seat beneath said rolled-over edge, and an annular yieldable gasket member disposed between the seat on 30 said annular member and the seat beneath said rolled-over edge for sealing the connection between said pot type receptacle and said housing.

2. In a pot type furnace a housing terminating in an upstanding annular member, a concave seat formed in said upstanding annular member, a pot type receptacle having an annular rim of U-shaped contour extending over said upstanding annular member, 45 the underface of said rim being concave downwardly in cooperative alignment with the concave seat on said upstanding annular member, and a compressible gasket secured in the concave seat in said upstanding annular member and occupying a position between said seats for sealing the passage therebetween.

3. In a pot type furnace, a furnace chamber, a top plate member in said chamber terminating in a central annular rim, a pot depending concentrically within said rim, said pot having an annular edge thereon, complementary curved faces on the said annular edge of said pot and the annular rim of said 55 top plate member, and a compressible gasket confined within a concave seat in the annular rim of said top plate member and secured between said complementary faces.

4. In a pot type furnace, a furnace chamber, a top plate on said chamber, said plate

terminating in a central annular rim, a pot depending in said chamber within said central annular rim, the edge of said pot being rolled over and projecting beyond said central annular rim, complementary faces on said rolled over edge and upon said annular rim, and a compressible gasket secured within an annular seat in the face of said annular rim and located between said complementary faces for sealing said chamber with respect to said pot.

In testimony whereof I affix my signature.

LEON C. KOENIG.
